UNITED STATES PATENT OFFICE.

CHARLES A. WEBER, OF LORAIN, OHIO, ASSIGNOR TO THE THEW SHOVEL COMPANY,
OF LORAIN, OHIO, A CORPORATION OF OHIO.

POWER SHOVEL HOISTING MECHANISM CONTROLLING MEANS.

Application filed October 3, 1921. Serial No. 504,995.

To all whom it may concern:

Be it known that I, CHARLES A. WEBER, a citizen of the United States, residing at Lorain, in the county of Lorain and State of Ohio, have invented certain new and useful Improvements in Power Shovel Hoisting Mechanism Controlling Means; and I do hereby declare the following to be a full, clear, concise, and exact description of the invention, such as will enable those skilled in the art to which it appertains to make and use the same.

This invention relates to power shovel hoisting mechanism controlling means, and consists in certain improvements in the construction thereof, as will be hereinafter fully described and pointed out in the claims.

In the practical use of power shovels, crane mechanisms, and the like, it has been found desirable to simplify the operations required, in order to operate the controlling mechanism for the hoisting means, since in the ordinary commercial construction it has been found that it is sometimes impossible for the operator to manipulate variously operated levers quickly enough, one after the other, to accomplish the most desirable controlling result, and it is an object, therefore, of my invention to so arrange the controlling mechanism of a power shovel or crane whereby the hoisting apparatus may be manually controlled by foot to lower the load and to maintain the shovel or bucket at any desired elevation, the same being accomplished in a mechanism of simple construction and with a minimum of manual effort.

It is a further object of my invention to so accomplish the result sought that the mechanical effort required will be natural and wherein the second part of the operation,—that of locking the bucket or shovel in a given elevated position—will be accomplished as a continuation of the effort required in causing the first part of the operation, that is, the operation whereby the hoisting clutch mechanism is disconnected to permit the lowering of the shovel or bucket.

Another object of my invention is to enable the operator, by merely operating a foot pedal, to lower the shovel or bucket and by a further depressing of the pedal to stop

the downward movement of the shovel or bucket whenever this is desired.

Another object of my invention consists in the improvements in the apparatus operating under the control of the foot operated pedal, and as will be later described.

Other objects of my invention and the invention itself will be more apparent by reference to the accompanying drawings, in which—

Fig. 1 shows a plan view of a portion of a steam shovel mechanism in which my invention is embodied. This view shows the controlling levers, a view of the intermediate controlling links and a clutch, said clutch being associated with the hoisting drum of a steam shovel; also a view of a foot pedal, a clutch controlling ram under the control of the foot pedal and a foot pedal operated brake.

Fig. 2 shows a side elevational view of a portion of the apparatus shown in Fig. 1.

Fig. 3 shows a view similar to Fig. 2, some of the intervening apparatus being removed, so as to expose the brake mechanism.

Fig. 4 shows a vertical cross section of the steam ram and steam ram controlling means, the mechanical link connecting the valve controlling means, and the brake foot pedal being indicated in this figure.

Referring now to the various figures, in all of which like parts are indicated by like reference characters, at 2 is shown an engine cylinder, of which one or more may be provided, containing a piston, said piston adapted to rotate a shaft 4 by means of a piston rod 5 attached to the piston and a reciprocating driver rod 6. The engine having the cylinder 2 is adapted to be operated by steam power and for the purpose of rotating the hoisting drum 30, said drum having secured thereto a friction wheel 39. The hoisting drum 30 is mounted on a shaft 31.

The shaft 31 is carried by bearings 32 in the frame 33. A friction clutch band 34 is adapted to be contracted to grip the hoisting drum friction wheel 39. The friction band is anchored by means of a bolt 35, said bolt passing through a pin 36 and being secured thereto on either side by nuts 37, said pin being mounted on the gear wheel 38. The

friction band is adapted to be contracted by having its other end 49, which is carried on a pin 40, moved thereby in the direction of the bolt 35, securing the other end of the 5 band.

The pins 40 and 43 are adapted to rotate about a center crank shaft journal 41, being disposed on different radii extending substantially at right angles one from the other, 10 the center of rotation comprising the journal 41. Therefore, when it is desired for the clutch band to grip the clutch drum, the same is accomplished by longitudinally moving the clutch operating link member 42, 15 which has an opening in its upper end, through which opening the pin 43 projects, the longitudinal movement of the member 42 in an upward direction, therefore, causing the pin 40 to be moved in a counter-clockwise direction about the center crank journal 41.

The clutch operating link 42 is caused to move the pin 43 up or down to operate the clutch, or to release it by the action of 20 the steam ram having a casing shown at 24, a piston 47 and piston rod 25. The motion of the piston rod is communicated to a pair of link members 26, to which it is secured by a pin 27, the said link members 25 being adapted to operate a crank shaft 46 having crank arms 45 and 48. Two crank arms 45 are secured to shaft 46, operating as one, the end of each containing an elongated perforation 101 adapted to embrace 30 lugs 50 extending through the said perforation, the said lugs being carried on a collar 102, and which collar fits within a groove contained in a collar 44, said collar being longitudinally movable on the shaft 31 and 35 having a connection with the clutch operating link 42. Thus, when the piston rod 25 is reciprocated, the link 42 will also be reciprocated to clutch or unclutch the brake band 34. The action of the piston 47 is controlled by a controlling valve 51, operating 40 over the ports 52 and 53, said valve being provided with a valve port 54 adapted to connect either the port 52 or 53 with an exhaust port 55, the exhaust port leading 45 to the exhaust passage 56. Steam enters 50 one or the other of the ports 52 or 53 as it is uncovered by the valve 51. As shown, the port 53 is open and steam entering the 55 said port the engine piston 47 will be driven to the left, as seen in Fig. 4. With the valve in this position, steam is exhausting by way of the passage 57, the valve port 54, the exhaust port 55 and the exhaust passage 56.

It will be observed that by moving the 60 valve 51 on its seat to the right, the port 53 will be covered by the port 54 and the port 52 will be uncovered, thus making a passage for exhaust steam between the port 53 and the exhaust port 55, and at the same time opening the port 52 for the ingress of

steam to the cylinder at the left of the piston 47, said piston then being caused to move, as shown in Fig. 4, to the right. Thus the clutch may be contracted or expanded to grip or release the clutch drum, as may be desired, depending upon the position of the valve 51 on its seat within the valve casing 24.

In order to operate the valve 51 by foot, I have provided a connecting link 27' between the foot pedal 16 and the lever arm 22, the connecting link being pivoted at 23 and 20 to the lever arm 22 and the foot pedal 16, respectively. The lever arm 22 is adapted to rotate on a shaft 85 to which 75 it is keyed by keys 18. The lever arm 22 terminates on its lower end in a projecting controlling cam 87, which, as shown in Fig. 4, projects into the recess 88 of the valve member 51 and is adapted when the arm 22 is rotated on the shaft 85 to propel the valve member 51 to the right and back to the left, as may be desired. The valve member 51 has its upper portion so shaped that when the valve 51 is moved to its extreme 90 right-hand position, the projection 87 will ride upon the curved surface 89 of the valve member 51, but without further moving the valve member.

The moving parts are so related and inter-connected that in the embodiment of my invention illustrated, when the valve is in the position illustrated in Fig. 4, that is, when the pedal is depressed, steam will enter the right portion of the cylinder through the port 53, to move the piston 47 to the left, thus causing an unclutching of the engine from the hoisting drum and the hoisting drum would thereupon be released from the propelling influence of the engine, and the power shovel or dipper of the device, which may have been previously elevated, would by gravity descend, causing an unwinding of its hoisting cable on the drum, this motion being suitably retarded by additional pressure placed by the foot of the operator on the pedal 18 of the pedal member 16. This retarding is accomplished by rotating the pedal shaft 11 to which the pedal member 16 is non-rotatably secured, the shaft 11 carrying, at a point remote from the pedal and below the brake mechanism (shown best in Fig. 3), a brake operating lever 12, said lever being connected by a tie-rod 13 to an end 17 of the brake band, the other end 3 of the brake band being rigidly secured at a point 91 by a tie-rod 92 to the frame 33 of the mechanism. 110

The brake band 93 having ends 3 and 17 is adapted thereby to be contracted to grab 125 the brake drum 94 more or less tightly, depending upon the degree of pressure exerted by the operator on the pedal 18 of the pedal member 16. By depressing the foot pedal 16 to an extremely low position, shown by 130

dotted lines in Fig. 3, the pedal member 16 may be latched under a hook latch member 95, said hook latch restraining the pedal member 16 from returning to upper normal position, as shown by the solid lines in Fig. 3, under the retractile power of the spring 15, which it otherwise would do. This pedal member may be maintained in fully operated hoisting drum braking position whenever desired, as, for instance, when the machine is traveling, or when it is desired to leave the machine inoperative for a period, or at any other time, for any other reason it is desired to maintain the dipper or bucket in any given elevated position.

Although the hoisting boom and other power shovel or crane apparatus usually associated with the mobile power shovel or crane mechanism is not specifically illustrated in the drawings, being omitted for the sake of simplicity of disclosure of the parts described, it will be understood that such parts are used in connection with a boom or like equivalent device having a shovel, or the equivalent means, on its end, over which a hoisting cable is adapted to pass, the cable connecting the bucket or dipper mechanism to the hoisting drum over which it is adapted to be wound.

For a more complete showing of such a structure, I refer to my copending application, Serial No. 417,093, filed October 15, 1920. My invention, however, may be used in connection with other arrangements wherein a cable wound over a drum may not be employed.

Having thus described my invention in a specific embodiment, I wish it to be understood that numerous and extensive departures from the embodiment herein illustrated and described may be made, but without departing from the spirit of my invention, which is defined in the following claims:

1. In combination, a hoisting mechanism comprising a hoisting drum, a source of power, a clutch, said clutch when operated adapted to cause the rotation of the said drum by the said source of power, a foot operated lever, a brake, said brake adapted to oppose the rotation of the said drum, a source of fluid pressure, a cylinder, a piston, a piston rod, and mechanical link connections between the said piston rod and the said clutch, means to admit fluid under pressure from the said source of pressure to the cylinder on either side of the said piston, said foot operated lever being adapted to control the flow of fluid pressure to the said cylinder and other link connections between the said lever and the said brake, whereby the lever controls the operation of the said brake.

2. In combination, a hoisting mechanism comprising a hoisting drum, a source of

power, a clutch adapted to connect said source of power with said drum and cause rotation thereof, a power operated mechanism for operating said clutch, a brake mechanism adapted to oppose the rotation of said drum, and means connected to said power operated mechanism for operating the clutch and to said brake mechanism to simultaneously move said clutch and said brake in opposite directions of application to said drum.

3. In combination, a hoisting mechanism comprising a hoisting drum, a source of power, a clutch adapted to connect said source of power with said drum and cause rotation thereof, a power operated mechanism for operating said clutch, a brake mechanism adapted to oppose the rotation of said drum, and a single means connected to said clutch operating mechanism and to said brake mechanism to control the operation of said clutch and said brake.

4. In combination, a hoisting mechanism comprising a hoisting drum, a source of power, a clutch adapted to connect said source of power with said drum and cause rotation thereof, a power operated mechanism for operating said clutch, a brake mechanism adapted to oppose the rotation of said drum, and a foot operated lever connected to said clutch operating mechanism and to said brake mechanism to simultaneously effect various relations of said clutch and said brake in its normal, intermediate and fully depressed positions, the clutch being engaged and the brake released when said foot lever is in normal position, the clutch being disengaged and the brake engaged when said foot lever is in intermediate position, and the clutch being positively disengaged and the brake being positively disengaged when said foot lever is in final position.

5. In combination, a hoisting mechanism comprising a hoisting drum, a source of power, a clutch adapted to connect said source of power with said drum and cause rotation thereof, a power operated mechanism for operating said clutch, a brake mechanism adapted to oppose the rotation of said drum, a foot lever connected to said clutch operating mechanism and to said brake operating mechanism to effect various relations of said clutch and said brake with said drum, a spring to retain said lever in normal position to engage said clutch with and disengage said brake from said drum, and means to lock said foot lever in final depressed position to disengage said clutch and engage said brake with said drum.

6. In combination, a hoisting mechanism comprising a hoisting drum, a source of power, a clutch adapted to connect said source of power with said drum and cause

rotation thereof, a power operated mechanism for operating said clutch, a brake mechanism adapted to oppose the rotation of said drum, a single means connected to said clutch operating mechanism and to said brake mechanism to control the operation of said clutch and said brake, and means

for retaining said single controlling means at each extremity of its movement.

In witness whereof, I have hereunto ¹⁰ signed my name this 25th day of September, 1921.

CHARLES A. WEBER.
